UNITED STATES PATENT OFFICE.

EDWIN C. CULLEN, OF COLORADO, TEXAS.

COMBINATION-TOOL FOR MANIPULATING WIRE.

SPECIFICATION forming part of Letters Patent No. 709,749, dated September 23, 1902.

Application filed February 8, 1902. Serial No. 93,161. (No model.)

To all whom it may concern:

Be it known that I, EDWIN C. CULLEN, a citizen of the United States, and a resident of Colorado, in the county of Mitchell and State 5 of Texas, have invented a new and Improved Combination-Tool for Manipulating Wire, of which the following is a full, clear, and exact description:

My invention relates to wire-forming implements, and more particularly to a convenient hand-tool for bending, straightening, shortening, and otherwise manipulating the wires ordinarily used in the construction of fences.

15 The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a plan view of my device. Fig. 2 is a fragmentary elevation showing one edge 25 of the tool and its appurtenances, and Figs. 3 and 4 are fragmentary elevations showing the opposite edge of the tool in use.

The tool can be made of any suitable material and of any desired size; but I preferably make it of steel and of the size indicated in the drawings. A longitudinal head *a* is provided with a handle *b* and with a bifurcated claw *c* of the type sometimes designated as a "cow's foot." A cylindrical boss *d* is integrally mounted upon the head *a*, and at right angles to this boss is a substantially cylindrical member *e*, provided with a slot *f*, the same constituting a former for wire. A similar member *g*, provided with a similar slot *h*, 35 constitutes another former, the two formers being so arranged that the slots are in alignment. A longitudinal arm *i* is disposed at right angles to the head *a*, and a link *k* engages a hook *l*, mounted upon said arm. Upon 40 the free end of the link *k* is a longitudinal comb *m*, which is used for the purpose of temporarily securing a wire, as hereinafter described. A strap of leather *n* is loosely pivoted upon a hook *o* on the comb *m* and is free 45 to engage or disengage a hook *p* on the head 50

a. This strap of leather is for the purpose of normally holding the comb *m* in the closed position (indicated in Fig. 1) when the comb is not in active use. The head *a*, taken together with the handle *b* and the longitudinal arm *i*, constitutes an L-shaped lever.

The tool can be used in various ways. For instance, if it be desired to splice a broken wire the ends of the wire are brought into the slots *f* *h* of the formers *e* *g*, and the tool is revolved bodily around, so as to bend the wire back upon itself, as indicated in Fig. 4. In doing this a little skill is necessary, as the wires must be brought upon the same side of the tool; otherwise it will be difficult to make the splice. Where it is desired to merely take up the slack of the loose wire, the tool is placed upon the wire and then twisted bodily around, bringing the wire into the position indicated in Fig. 3. The splice can readily be effected with the wire in this position. If it be desired to pull the wire bodily endwise toward a fence-post, this may be done in the following manner: The comb *m* is released by unhooking the leather strap *n*. Then the end of the loose wire is dropped into the slot *e*, and the wire is carried once or twice around the longitudinal arm *i* and then around the cylindrical former *d*, so as to have the wire thoroughly secured upon the tool. Then using the tool as a lever it is placed against the post, the cylindrical former *d* being used as a fulcrum, and then the handle is borne upon until the wire is pulled around as tightly as desired. The handle *b* is moved around until the comb *m* can be brought into engagement with the tightened wire and hooked over the same, and the tool now being released will hold the wire temporarily for any desired purpose. The bifurcated claw *c* is used for taking up short splices, as indicated in Fig. 1.

The above instances are only a few of the many ways in which this tool can be used to advantage. Several other uses will suggest themselves to people skilled in the art to which the invention relates.

The formers *e* and *g* may be used separately for tightening the wire and for making splices shorter than those made with the cow's foot *c*.

Having thus described my invention, I claim as new and desire to secure by Letters Patent—

1. A combination - tool for manipulating wire, comprising a handle, a bifurcated claw, a plurality of formers provided with slots for engaging the wire, and a cylindrical boss for temporarily securing said wire to the tool.
2. A combination - tool for manipulating wire, comprising a handle, a bifurcated claw, a plurality of formers provided with slots for engaging the wire, a cylindrical boss for temporarily securing said wire to the tool, a longitudinal arm disposed at right angles to said handle, and a comb flexibly connected with the said longitudinal arm for the purpose of temporarily engaging the wire.
3. A combination - tool for manipulating wire, comprising a longitudinal member provided with a handle, and with a pair of substantially cylindrical formers disposed parallel with each other and provided with slots, said slots being in alinement, and also pro-

vided with a cylindrical boss disposed with its axis at a right angle to the axes of the said cylindrical formers.

4. A combination - tool for manipulating wire, comprising a lever made of two longitudinal members disposed at right angles to each other, one of said members being provided with a comb flexibly connected therewith, and the other being provided with a bifurcated claw, a cylindrical boss, a pair of substantially cylindrical formers provided with slots, said slots being in alinement with each other and all for manipulating wire, and a fastening for temporarily securing said comb in a folded position when the same is not in active use.

In testimony whereof I have signed my name to this specification in the presence of two subscribing witnesses.

EDWIN C. CULLEN.
